(57) **CLAIM**

The ornamental design for a bottle as shown and described.

DESCRIPTION

FIG. 1 is a left, front perspective view of a first embodiment of a bottle;

FIG. 2 is a right, rear perspective view thereof;

FIG. 3 is a left view thereof;

FIG. 4 is a front view thereof, the rear view being identical;

FIG. 5 is a right side view thereof;

FIG. 6 is a rear view thereof, the front view being identical;

FIG. 7 is a top view thereof;

FIG. 8 is a bottom view thereof.

FIG. 9 is a left, front perspective view of a second embodiment of a bottle;

FIG. 10 is a right, rear perspective view thereof;

FIG. 11 is a left view thereof;

FIG. 12 is a front view thereof, the rear view being identical;

FIG. 13 is a right side view thereof;

FIG. 14 is a rear view thereof, the front view being identical;

FIG. 15 is a top view thereof; and,

FIG. 16 is a bottom view thereof.

The broken lines in the figures illustrate the portions of the design that form no part of the claimed design.
